Primary Examiner — Katherine A Holbrow*Assistant Examiner* — Riya Salil Kamat(74) *Attorney, Agent, or Firm* — Dunlap Bennett & Ludwig, PLLC(57) **CLAIM**

The ornamental design for a game board, as shown and described.

DESCRIPTION

FIG. 1 is a front perspective view of a game board, showing my new design;

FIG. 2 is a front elevation view thereof;

FIG. 3 is a rear elevation view thereof;

FIG. 4 is a left side elevation view thereof, the right side elevation is an identical image thereof; and,

FIG. 5 is a top plan view thereof, and the bottom plan view is an identical image thereof.

The evenly sized dash-dash broken lines shown in the drawings depict portions of the game board that form no part of the claimed design.

The unevenly sized dash-dot-dash broken lines shown in the drawings depict the bounds of the claimed design and do not form part of the claimed design.
